VANE PUMP

Warren R. Tucker and George A. Waldie, Dayton, Ohio, assignors to The Hydraulic Development Corp. Inc., Wilmington, Del., a corporation of Delaware

Original application February 6, 1941, Serial No. 377,769. Divided and this application December 17, 1941, Serial No. 423,338

1 Claim. (CL. 103—136)

This invention relates to fluid pumps of the vane type, and more particularly to fluid pumps which are adapted for circulating liquids and for producing pressure with said liquids for actuating various operating elements.

In this invention the fluid pump is adapted to pump hydraulic fluid from a storage chamber to a hydraulically actuated device, such as a press, molding machine or other conventional hydraulically actuated mechanisms. There are many types of pumps which are adapted for placing fluids under pressure, but the types of pumps which have heretofore been used in placing liquid under pressure have been limited to the radial piston type of liquid pump. This type of pump produces high pressure with relatively low power consumption and has been the most efficient type for use in producing high fluid pressures for actuating mechanical presses requiring high fluid pressures.

In this invention, however, mechanical alterations have been made to a vane type of fluid pump which makes it adaptable for producing high fluid pressures, and particularly, high liquid pressures which are of sufficient value that the pump can be used as the pressure supply mechanism for actuating hydraulic mechanisms. In former vane type pumps considerable difficulty has been encountered in producing high pressures, since the liquid slip past the vane has been considerable. There have been attempts to secure the vanes in constant engagement with the cylindrical wall of the cylinder and to increase the volumetric efficiency of vane type pumps when used for liquid delivery. These applicants have produced a mechanism which promotes the maximum efficiency of a vane type liquid delivery pump and which retains the vanes of the pump in constant engagement with the cylindrical wall of the cylinder to prevent liquid slip past the ends of the vanes which are in engagement with the cylinder wall.

It is an object of this invention to provide an improved pump structure for use as a liquid pump.

It is another object of the invention to provide means for retaining the vanes of a vane type pump in engagement with the cylindrical wall of the cylinder.

It is another object of the invention to provide a mechanism in accordance with the foregoing object which resiliently urges the vanes outwardly into engagement with the cylindrical wall.

It is another object of the invention to provide a vane type pump having a plurality of vanes

wherein a cylindrical member engages the vanes in a manner that all of the vanes are retained in constant engagement with the cylindrical wall of the cylinder.

5 It is another object of the invention to retain the vanes of a vane type pump in engagement with the cylinder wall by means of fluid or liquid under pressure.

10 It is another object of the invention to provide a vane type liquid delivery pump having means for retaining the vanes in constant engagement with the walls of the cylinder, and which cylinder is adapted to be moved with respect to the pump rotor in order to change the 15 direction of delivery of the pump.

It is another object of the invention to provide a variable delivery reversible flow liquid pump of the vane type having a mechanism for maintaining the vanes in engagement with the cylinder 20 wall, and which is constructed and arranged for movement of the cylinder with respect to the rotor without effecting the mechanism for maintaining the vanes in constant engagement with the cylindrical wall of the cylinder.

25 It is another object of the invention to provide a variable delivery reversible flow fluid pump with means for conducting fluid under pressure under the vanes to force the same outwardly into engagement with the cylinder walls, wherein means 30 are provided for changing the flow of pressure fluid in the conducting means when the flow of fluid through the pump is reversed.

It is another object of the invention to provide a vane type fluid pump wherein the vanes are 35 a loose fit within cooperating slots in the rotor to permit fluid to enter the slots which, when under pressure, will force the vane outwardly into engagement with the cylindrical wall of the cylinder.

40 It is another object of the invention to provide a vane pump in accordance with the foregoing object wherein the vanes can tilt angularly with respect to the slot to seal the slot against the passage of delivery of high pressure fluid to the 45 low pressure side of the pump.

It is another object of the invention to provide a vane type pump in accordance with the aforementioned object wherein the vane can tilt angularly in either direction with respect to the slot and the seal between the high and low pressure sides will be effective in either position of the vane.

50 It is another object of the invention to provide a variable delivery reversible flow fluid pump of the vane type having vanes which are a loose fit

in the rotor slots for the same, and which has the advantages aforementioned for this type pump.

It is another object of the invention to provide a vane type pump for liquid delivery which has a straight-through liquid flow through the pump.

Further objects and advantages will become apparent from the description and the drawings.

In the drawings:

Figure 1 is a longitudinal cross-sectional view of the pump of this invention.

Figure 2 is a transverse cross-sectional view of a portion of the pumping mechanism showing a modified arrangement of pumping mechanism.

Figure 3 is a perspective elevational view of one of the vanes used in the pump of Figure 2.

In this invention the fluid or liquid pump consists of a casing having passageways 11 and 12 extending therethrough. A substantially rectangular member 17 forms a cylinder block within which there is provided a cylindrical bore 18 which extends transversely of the block 17. This bore 18 forms the cylinder wall of the cylinder of the pump. The cylinder block 17 is carried between parallel faces 19 and 20 provided on the casing 10, the parallel faces provided on the cylinder block 17 slidably engaging the faces 19 and 20 to permit the cylinder block 17 to be reciprocated thereon. A passageway 21 provided in the cylinder block 17 communicates with the passageway 11, and a passageway 22 provided diametrically opposite the passageway 21 communicates with the passageway 12.

A rotor member 23 has a body portion 24 positioned within the cylinder bore 18. One side of the body portion 24 carries a flanged portion 25 which engages the wall of the cylinder block 17, as indicated at 26. An end plate 27 is secured to the rotor body 24 by means of the bolts 28 and is adapted to engage the opposite face of the cylinder block 17, as indicated at 29.

The flanged portion 25 of the rotor 23 has a hub 30 extending therefrom which is carried by the inner race 31 of a ball bearing 32 which is positioned within a recess provided in the casing 10. The end plate 27 has a hub 34 which carries a bushing 35. The bushing 35 is carried by the inner race 36 of a ball bearing 37 mounted within a recess 39 of the end plate 40 of the casing 10. The end plate 40 is secured to the casing 10 by means of the bolts 41 and encloses the pumping mechanism within the casing 10. The hub 30, on the flanged portion 25, extends outwardly of the casing 10 and provides a drive shaft 42 which can be suitably connected to a driving mechanism, such as an electric motor or any other suitable power device.

A conventional oil seal 43 is positioned around the drive shaft 42 and is retained within a recess 44 in the casing 10 by means of a closure plate 45.

The body 24 of the rotor 23 is provided with a plurality of radial slots 46 in each of which there is positioned a vane 47. The vanes 47 have their outward ends in engagement with the cylindrical bore 18 and which cooperate with the cylindrical bore 18 and the body of the rotor 24 to provide means for pumping fluid between the passageways 11 and 12. The vanes 47 have their inner ends extending within a central bore 48 provided in the rotor body 24. The bore 48 extends into the flanged portion 25 and a cooperating bore 49 is provided in the plate 27. The vanes 47 are all of equal length and since the cylinder bore 18 is eccentric with respect to the rotor body 24 when the pump is in operating position, it can

readily be seen that the vanes 47 will extend into the bore 48 in the rotor body 24, and that the extending portion of each vane will have a different length according to the position of the vane with respect to the eccentric positioning of the cylinder bore 18 with respect to the rotor body 24.

In order to retain the vanes 47 in constant engagement with the cylinder bore 18 a frusto-conical pin 50 is positioned within the bore 48 and is of such diameter that the surface thereof engages a complementary surface on each of the inner ends of the vanes 47. Since the vanes 47 are all of equal length it can be seen that the pin 50 will be arranged concentric with respect to the cylindrical bore 18, and since the end surfaces 51 of the vanes 47 have a form complementary to that of pin 50, it can readily be seen that the vanes 47 will remain in constant engagement with the cylindrical bore 18 at all points throughout their rotation about the pin 50. The pin 50 thus becomes a member which is floated by the inner ends of the vanes 47, which provides a rigid bearing surface upon which the vanes ride in order to mechanically urge the same into constant engagement with the cylindrical bore 18.

These complementary frusto-conical surfaces on the pin 50 and the vanes 47 cooperate, as indicated at 52, to provide surfaces by which the radial position of the vanes 47 can be altered. Longitudinal or axial movement of the pin 50 forces the vanes 47 outwardly to the right as seen in Figure 1 to thereby decrease the clearance between the end of the vanes 47 and the cylinder bore 18.

The adjusting means for axially or longitudinally moving the pin 50 consists of a cylindrical plunger 53 mounted within a bore 54 provided in the hub 30 of the rotor 23. The plunger 53 extends into the bore 49 within the body 24 of the rotor and engages the pin 50, as indicated at 55. A compression spring 56 is positioned between the end wall 57 of the plunger 53 and the end wall 58 of the bore 54, which spring tends to urge the tapered pin 50 to the right, as indicated in Figure 1. The taper on the pin 50 extends from the left to the right thereof, viewed in Figure 1, so that movement of the pin 50 to the right will tend to force the vanes 47 outwardly into engagement with the cylinder bore 18. The spring 56 thus provides means for relentlessly urging the tapered pin 50 into pressure engagement with the vanes 47. A small hole 53a is provided in the end of the plunger 53 to prevent the plunger from acting as a piston.

An adjusting screw is provided in the end plate 27 and engages a friction button 60 which engages the righthand end of the tapered pin 50. The adjusting screw 59 is in threaded engagement within the hub 34 of the end plate 27. An inspection plate 61 is provided on the end plate 40 of the casing 10 to permit access to the adjusting screw 59. Means for binding the adjusting screw in position after an adjustment has been made is provided on the hub 34 of the end plate 27 and consists of a portion 62 of the hub which has been separated from the main body thereof by means of a slot 63. A screw 64 extends through the portion 62 and into threaded engagement with the body of the hub 34. When the screw 64 is tightened the flanged portion 62 will bind upon the threads of the adjusting screw 59 to retain the same in its properly adjusted position. A drain opening 66 is provided in the

casing 18 to remove liquid or fluid leaking into the casing from the pumping mechanism.

The mechanism just described provides a fluid or liquid pump wherein the fluid flow through the pump is an in-line flow, whereby minimum resistance to fluid flow is obtained and which provides a structural arrangement whereby the fluid can be circulated through the pump without the necessity of passing through a center pintle.

The pump can be operated as a variable delivery pump, or the fluid flow therethrough can be reversed. As previously described the cylinder block 17 is in sliding engagement with the surfaces 19 and 20 of the casing 18. The plane of eccentricity of the cylinder bore 18 with respect to the rotor 23 is parallel to these surfaces 19 and 20 so that reciprocation of the cylinder block 17 parallel to the surfaces 19 and 20 alters the eccentricity of the cylinder bore 18 with respect to the body 24 of the rotor.

In Figure 2 there is disclosed a modified form of pump rotor which can be used in the pump previously described. When used in the pump described with regard to Figure 1, the only modification required of this pump is the removal of the tapered pin and the operating mechanism for the same.

This modified form of rotor consists of a rotor body 95 which is positioned within a cylinder bore 96 provided in a cylinder block 97. Suitable end plates are provided on the rotor 95 for sealing the ends of the bore 96 and thereby providing a pumping chamber. The structure of these end plates has been previously described and the specific manner of mounting the same in the pump casing has also been described, so that the pumping mechanism in this modified form contains the same advantages of minimum of friction developed between the working parts. Suitable bolts 98 extend through the rotor and secure the end plates thereto.

A plurality of slots 99 extend longitudinally of the rotor 95 and also extend radially thereof. Vanes 100 are adapted to be positioned within the slots 99 for reciprocation therein. It is of course understood that when the pump is in operating position the cylinder bore 96 is eccentric with respect to the rotor 95, which rotor rotates concentric with respect to the bearing support for the same. It is also understood that the cylinder bore 96 is shiftable with respect to the rotor 95 to vary the flow of the pump or to reverse the flow thereof.

The vanes 100 have a cross-sectional dimension which is less in thickness than the width of the slot in which the vane is to operate, thereby providing clearance between the face surface 101 of the vane and the face surfaces 102 of the slot. The faces 101 of the vanes 100 are provided with an undercut portion toward the lower edge thereof which is angularly disposed with respect to the faces 101 so that an angular face 103 is provided near the central portion of the lower edge of both of the faces 101 on each of the vanes 100. The outer edge of the face 101 remains rectangular in shape as shown at 104.

With the vanes 100 constructed as just described, it can readily be appreciated that fluid or liquid can pass between the surfaces 101 and 102 of the vane and slot and enter the chamber 105 just below the vane 100, and as the fluid or liquid is under pressure that the pressure of the fluid will act upon the end of the vane 100 to

force the vane 100 outwardly into engagement with the cylinder bore 96.

However, when the pump is first started with no pressure existing on either side thereof, the initial rotation of the rotor 95 causes the vanes 100 to be moved outwardly due to the centrifugal force. Also, the rotation of the rotor 95 causes the vanes 100 to assume an angular position with respect to a slot 102 so that the end of the vane lags behind the slot thereby providing a definite passageway 106 between the forward face of the vane 100 and the forward face of the slot 99 whereby fluid will enter the chamber 105. When the vane 100 assumes this position the rear face 15 of the vane 100 will engage the upper and rearward edge of the slot 99, as indicated at 107, thereby providing a sealing engagement therebetween for sealing the chamber 105 from the chamber 108 which trails the vanes 100. It is understood that each of the vanes 100 has a chamber in advance thereof and a chamber which trails the same, the chamber in advance of the vane being the compression chamber or fluid moving chamber, while the chamber trailing the vane is the suction chamber. The pressure in the chamber in advance of the vane 100 will thus provide a rearward pressure on the vane 100, to cause the rear face thereof to seal against the upper and rearward edge of the slot 99, which is in direct proportion to the pressure in the chamber in advance of the vane. Since the passage 106 permits fluid or liquid to enter the chamber 105 the vane 100 will be forced outwardly into engagement with the cylinder bore 96 by a force 30 which is proportionate to the surface area of the inner edge of the vane exposed to the pressure, this force being relieved to some extent by the pressure exerted on the outer edge surface of the vane 100. However, since the inner edge 35 surface of the vane has a greater surface area exposed to the pressure than the outer surface edge the resultant of the forces will be such that the vane will be moved outwardly into engagement with the cylinder wall 96. While the fluid 40 or liquid pressure is also exerted upon the rear face of the vane 100 below the edge 107, yet the surface area of the vane exposed to this force is less than the surface area exposed on the forward face thereof so that the resultant of the forces 45 will be a rearwardly directed force opposed to the direction of rotation of the rotor.

This condition is true at all points on all vanes of the rotor, with the exception of one position and that is the position of the vane passing over 50 the land between the high and low pressure sides of the pump. When the vane is in the land between the high and low pressure sides of the pump the pressure from the high side of the pump will overcome the drag upon the vane 55 caused by rotation thereof whereby the vane will be forced forwardly into engagement with the forward wall of the slot 99, as indicated at 109. However, the same conditions of sealing between high and low pressure side of the pump exists as 60 heretofore described, except the vane is in the opposite angular position.

It may thus be seen that the structure just described provides a pumping mechanism wherein the vanes are retained in engagement with the cylinder bore 96 by a pressure which is in direct proportion to the pressure existing on the high side of the pump, or in proportion to the pressure existing in the chamber in advance of each of the vanes so that as the pressure 65 against which the pump is working increases, the

sealing engagement of the vane with the cylinder bore 96 will be increased. Also, by the same course of events, the sealing engagement between the vane and the rearward edge of the slot 99 will be increased.

Since the angular face 103 is provided on both sides of each of the vanes 100, it can readily be appreciated that the pump can circulate fluid or liquid in either direction of flow through the flow passages 110 and 111, and that the vanes 10 will function in the same manner as heretofore described.

While the forms of the pump heretofore described are preferred forms, yet there are mechanical modifications thereof which can be developed and we desire to comprehend within our invention these various mechanical modifications.

This application is a division of my copending application Serial No. 377,709, filed February 6, 1941, patented July 18, 1944, No. 2,354,076.

Having thus fully described our invention, what we claim as new and desire to secure by Letters Patent is:

A reversible variable delivery pump including, 25
a cylinder having fluid flow passages, a rotor

having therein a plurality of radially and axially extending slots, said rotor being journaled within said cylinder, said cylinder and rotor being relatively movable to change the eccentricity between their axes, a generally rectangular vane in each slot, respectively, each vane having an axial dimension greater than its radial dimension, and a thickness substantially less than the corresponding dimension of its slot whereby each vane tilts circumferentially within its slot in a direction depending upon the direction of rotation of said rotor, the outer end of each vane slidably engaging the walls of said cylinder and being shaped to give, when so tilted, substantially line contact along elements of said cylinder, each vane, when so tilted having substantially line contact with its slot on opposite sides thereof, each vane having its opposed faces chamfered along and adjacent a mid-portion of its inner edge, whereby fluid under pressure may have access to the slots when the vanes are so tilted, to thereby urge each vane radially outward.

WARREN R. TUCKER.
GEORGE A. WALDIE.
